CLAIM

The ornamental design for a front plate for an electronic navigation instrument, as shown and described.

DESCRIPTION

FIG. 1 is a perspective view of the front plate for an electronic navigation instrument of the present invention; FIG. 2 is a front elevational view thereof; FIG. 3 is a left side elevational view thereof; FIG. 4 is a right side elevational view thereof; FIG. 5 is a top plan view thereof; and, FIG. 6 is a bottom plan view thereof.

The broken line showing is for illustrative purposes only and forms no part of the claimed design.
